PUMP FOR CONCRETE, MORTAR, AND THE
LIKE

Roger Londais, Paris, France

Application October 27, 1937, Serial No. 171,386
In France November 4, 1936

8 Claims. (Cl. 103—227)

My invention relates to a reciprocating pump for handling liquids transporting pasty or solid material such as concrete, mortar, and the like, which pump may also, without any further independent mechanical valve, pump the scavenging and cleansing liquid for the piping.

One of the chief objects of my invention is an improved construction of pumps of the type comprising independent one-piece rotary suction and discharge valves located near one another. I have found in contradistinction with prior work, that the operation of these automatic valves and consequently that of the pumps themselves was greatly improved by the concrete passing diametrically through a widening and then narrowing automatic valve.

According to my invention therefore, in pumps of the type referred to the diametrical passageway through at least one rotary valve is widened at the end of said passageway, opposite to that which is adapted to register with the inlet or outlet means leading to or from the pump cylinder.

The widening of the valve merging into a predeterminedly narrowing part when suitably shaped, sized and located, allows a better and more regular suction of the mixture through the valve and furthers the movement of the larger stones or other solid bodies contained in the mixture, as it allows their escape into and out of the valve bodies at the moments of closing and opening.

The large surface of the widened part of the suction valve opening towards the feed hopper provides a passage for the transfer of a volume of material equal to that forced through the axial passage in the automatic valve through the obturating part engaging same.

The automatic discharge valve, the flared opening in which is adapted to face the delivery pipe, prevents a too sudden stopping of the flow of material and thus the tendency of said material to return backwards, the obturating action being performed through the part of the valve opposed to the widened part.

Heretofore the movement of the distributing means was controlled by a rotary or oscillating cam, provided with a groove adapted to guide a roller secured to a lever controlling the reciprocating distribution through a connection rod. As at each reversal of motion the starting is sudden, there is a sudden shock and consequent damage of the pump is produced.

My improved cam comprises operative positive portions providing a uniformly accelerated start

and a uniformly decelerated end of stroke. The cam follower is held in engagement by a counter-roller. This provides a greater mechanical yieldability, silence and life for the whole system. My improved cams are simple and economical in their manufacture. The outline is designed in accordance with the movements it is desired to obtain. The outline of the race of the counter-roller is machined through guiding of the model cam in an arrangement corresponding to the characteristics of use.

Although the metals used are very hard chiefly for the valve proper and its ring, the valves should not act uselessly as crushers or shearers and a compensating spring provides limitation of the stresses to a normal value during the closing movement.

When the pumping is at an end, the pipes should be emptied. There has already been used therefor either a current of compressed air or else an additional set of spring-urged valves arranged inside the concrete pipes ahead of the inlet valve and beyond the outlet valve. I have found it is possible to provide this emptying or scavenging without any additional independent valves, because my improved valves provide complete closure and allow the normal forcing of a cleansing liquid through the pipe without any further independent valve or the like, even for small forcing pressures. To this end, for maximum efficiency of the driving stroke, without any modification in the timing of the valves, the diametrical aperture in the suction valve is temporarily reduced to the size strictly required for the passage of the cleansing liquid. This reduction in size is obtained by means of a plug inserted in the aperture and held by a spigot the hollow head of which allows removal of the products which may have dried in the hole wherein it is held. Such plugs for changing the nature of the operation of a concrete or the like pump have never been proposed and form an important improvement for such pumps.

The concrete has a tendency to coat and to adhere to screw threads, and therefore I have provided protected screw closures for the parts connecting the delivery with the pump.

I will now describe by way of example a form of execution of my improved pump, incorporating the above features. This form of execution is illustrated in accompanying drawings.

Fig. 1 is a cross-section of the exemplification, the section passing through the longitudinal axis of the pump.

Fig. 2 is a cross-section of Fig. 4 along line II—II.

Fig. 3 is a longitudinal cross-section of the valve showing the manner of its construction.

Fig. 4 is an outer view of part of the pump.

Fig. 5 shows the sliding carrier of the fluid-tight system.

Fig. 6 is a cross section of a detail of the valve.

Figs. 7 and 8 show respectively a rotary and an oscillating grooved cam according to prior art.

Fig. 9 shows the cam according to invention.

Fig. 10 is a side view of the control system for the cam.

Fig. 11 is a plan view of the rotary cam of Fig. 7.

Fig. 12 is a detail partly sectional view of the controlling arm.

Fig. 13 shows a removable cleansing plug for the suction valve.

Fig. 14 is a cross-section thereof.

Figs. 15 and 16 are respectively top and bottom views of the plug.

Fig. 17 is a cross-sectional detail view of the plug.

Fig. 18 is an explanatory view of the pump scavenging arrangement.

Fig. 19 is a part sectional view of the protected screw closures.

As shown in Fig. 1, the pump comprises a main cast portion 20 provided with handling apertures 21 and with a base 22 resting on the ground. The suction valve is enclosed in a casing 23 having a partition in common with the casing 24 of the discharge valve. The outlet piping is shown at 25. The piston 26 reciprocates in the wear-resisting lining 27 held down by a plate 28 fitted against the ring 29; there is a water reservoir to the rear of said plate 28 at 30, a packing being provided between the piston and the reservoir wall at 31 and a cover 134 closing the reservoir. The valve casings 23 and 24 are each provided with a lining 32 secured by a key 33. The upper part of the valve casing 23 carries the feed hopper 34 inserted inside a frustoconical base 35 secured through angle bars and bolts 36—37 to the casing 23.

The piston 26 is provided with a packing comprising two oppositely directed stamped parts 38—39 separated by a washer 40. This packing is mounted axially on a rod-shaped extension of part 41 carrying the gudgeon-pin 45, said packing being held between a counternut 42 and a securing plate 43 by the nut 44 the head of which is protected. The gudgeon 45 is connected with the crank shaft 47 through the connecting rod 46. The actuation of the crankshaft 47 is performed through the toothed wheel 48 meshing with the pinion 49 keyed to the shaft 51. A pulley 50 secured to the same shaft 51 rotates inside the bearing 52 integral with the support 53 and is driven by the small pulley 54 driven in its turn by the motor 55 through the belt 56. Clutching means controlled by the lever 133 are inserted between the motor and the crankshaft 47 drive. The support 53 is secured to the motor carrying frame 57 through bolts 58 while said frame 57 is secured to the main portion or support 20 through bolts 59 of which only one is shown. The frame 57 has a central dish-shaped staying part, a discharge port 60 being provided for communication with a pipe 61 opening outside the side flange.

To the toothed wheel 48 and consequently to the crankshaft 47 is secured the cam 62 which 75 controls the rocking lever 63 carried by the shaft

64 and carrying the spindle 65 on the connecting rod 66; the spindle 67 surrounded by the spring 68 forms an extension for the connecting rod 66 which is furthermore connected by the lever 69 with the rocking spindle 70 for the suction valve 71. An entirely similar control system, not shown, is provided for the discharge valve 71'.

A valve 71 is shown in detail in Figs. 2 to 6. It includes a rocking spindle 70 with its control lever 69, said spindle being held with the interposition of the sleeve 73 inside the bearing 72 while the extension 74 of the spindle 70 is similarly held with its thrust plate 75, end ring 76 and cooperating bolt 77 inside the bearing 78 with the interposition of the sleeve 79. The lubrication is performed through 80 while a packing and a stuffing box are at either end of the spindle 70—74 at 81 and 82. The valve body 71 is provided laterally with a ring 83 held by a plate 84 and a countersunk screw 85. To either side of the valve recess or housing 23—24 is arranged a water reservoir 86—87 the walls of which allow the passage of the spindles 70—74 and which are tightly sealed at 129. These reservoirs may be drained through 88—89 and are provided with a fluid-tight rubber ring 129. To either side of the valve 71 and inside the corresponding reservoir, a ring is secured to the rocking spindle through the screw 90 and retains a small spigot 91 through the washer 92 and the screw 93. This small spigot is threaded and allows the annular plate 94 to slide over it. The annular plate 94 includes radial projections 95 and a longitudinally sliding spindle 96 engaging an aperture in the stationary ring. This annular plate 94 forms through its projections 95 a thrust bearing for the ring 97 which holds the packing 98 inside the lining 99 against the lining 32. The valve 71 has a hole 100 engaged by the small spigot 91 described above.

Figs. 10 and 12 show in detail the control means. The roller 101 rolls over the race of the cam 62 and the roller 102 keeps it constantly in contact as it rolls on the outside of the outline. The rocking spindle 65 rocking in its bearings 103 carries the slide 104 and the journal 105 receiving the compression spring 68 held by the dished part 106. The latter is held by the counter nuts 107 and 108 screwed over the spindle 67 engaging frictionally the sleeve 109 integral with the connecting rod or tube 66. It is possible to insert between these parts a packing 110. The connecting rod 66 also carries a threaded sleeve which receives the end of the connecting rod head 111 with its counter nut 112. The connecting rod head or its axis 113 is held in the journals 115 of the lever 69. The rollers 101 and 102 are mounted on axes 116 integral with the rocking lever 63 controlled by the cam 62 and acting on the spindle 67 and rod 66.

The plug 117 used for water pumping purposes shown in Figs. 13 to 16 with a detail in Fig. 17, includes a handle 118, a screw 119 having a spigot-shaped extension, a bronze ring 120, a passage for liquid 121, a boss 122 and a male enlargement 123.

The part 124 used for securing a pipe to the pump outlet (Figs. 1 and 19) and rotating around spindle 132 is provided with a protected screw 125 with large threads and a steel ring 126. The screw is shown with rounded threads and a head 127. Its shaft has two diameters, the smaller at 128 and the larger at 130 and bears against 75

parts 131—131', forming the flanges of the elements to be connected.

The detail of valve 71 or 71' (Fig. 3) shows how the diametrical passage is formed. The valve body is bored to a diameter T along the axis O—O. It meets another cylinder of same diameter having as axis a line X—X which is a further position of axis O—O after an angular shifting in the vertical plane of Fig. 3. The two cylindrical recesses described engage one another and the sharp ridge at their engagement is bevelled off as shown at 8. The bevelled part merges tangentially with the cylindrical portions through suitable machining. This forms a very smooth 5 perfectly continuous diametrical passage for the concrete.

As shown in Fig. 2 the valves 11, 11' are mounted with as little play as possible inside their lining 32 so as to limit theoretically the size of the bodies capable of passing between 11 and 32 to that of very fine particles smaller than the play due to rocking and mounting between the outside of the valves 11 and 11' and the inside of the lining 32. This allowable play is of one half millimeter. Moreover the passage of small particles inside this play is prevented in practice by greasing the outside of the valve and the inside of the lining 32.

The single outline cam 62 produces the positive suitably timed movements with a uniformly accelerated start and a uniformly decelerated end of stroke. It is obtained as follows (Fig. 9). The four strokes of the pump are provided by the four sections of the cam W, Z, W', Z' defined by the axes B—B and C—C as in the prior art (Figs. 7 and 8) with rotating or rocking cams. The positive drive sections Z and Z' are divided along the circumference of the cam into equal angular parts 1A to 8A. The negative drive sections W and W' ending at B—B and C—C must be tangentially connected with Z and Z'. The total radial thrust produced by the cam as the spindle 61 advances through a distance Y, is measured radially along B—B and is divided in as many portions as the portion of the circumference corresponding to the drive section Z' for example, 8. This division is unequal and follows the law of acceleration (1, 1+1, 1+1+1, 1+1+1+1) for the four first periods, the division for which is shown along B—B, the four following periods being arranged reversely (4, 3, 2, 1) as shown for greater clearness along C—C. From all the points of division arranged along B—B (and similarly along C—C), a portion of circumference is drawn and also rays from the centre of the cam through the points of division of the circumference. The points obtained by intersection of the corresponding radii and the portion of the circumference thus drawn define the outline of the cam to be obtained for the drive section Z (and similarly Z'). The actual cutting of the cam is provided by the cutter F.

The pump has been designed so that in normal operation, the suction of the piston being at an end, the suction valve 71 begins closing a little before the discharge valve 71' opens. During scavenging, the high pressure of the liquid which is being pumped through the machine does not build up until the opening 121 inside the plug 117 used for such scavenging purposes is covered. Similarly when the discharge is at an end, the automatic discharge valve must close before the opening 121 is uncovered for the passage of a fresh batch of scavenging or cleansing liquid.

The operation of the pump may be briefly described as follows: the feed hopper being filled with concrete or like material, the suction valve 11 opens under the action of the synchronized control system and the flaring portion of its diametrical passage opens towards the hopper. The material falls then through gravity as well as through the action of the vacuum caused by the return stroke of the piston. At the beginning of the movement the automatic discharge valve 11' is closed with a slight advance with reference to the movement of the automatic suction valve 11, so that at the end of the stroke of the piston 26, no return flow of the material can occur. The suction of the material through the pump piston fills the pump cylinder. When the piston has almost arrived at the end of its stroke, the synchronised control system of the automatic valves gives each of them a position reverse with reference to that occupied just before; the suction valve 11 is closed slightly before the opening of the discharge valve 11'. The latter closes again after discharge so as not to interfere with the material discharge outlet 25. The cycle of movements begins then over again.

The removable plug 117 is fitted inside the automatic valve 71. The feed hopper is then fed with the scavenging or the cleansing liquid, the pump is started and the concrete or similar material scavenged.

A pump such as described affords the considerable advantage of providing in succession normal pumping for concrete mortar and the like and pumping of the cleansing water without any further modification, addition or adjustment except for the insertion of the plug 117. 35

What I claim is:

1. A pump chiefly for concrete, mortar, and the like material comprising a cylinder, a piston, control means for making said piston reciprocate inside said cylinder, suction means for said cylinder including a rotary valve and a casing therefor provided with two substantially opposite openings one of which is in substantially immediate communication with the cylinder, exhaust means for said cylinder including a rotary valve and a casing therefor provided with two substantially opposite openings one of which is in substantially immediate communication with cylinder, said valves being provided each with a substantially diametrical passageway the ends of which are adapted to register with the corresponding openings of the corresponding valve casing while the end of the passage way for one of said valves, which end is adapted to register with the casing opening remote from the cylinder, has a flaring shape, means for controlling said valves in operative relationship with the movements of the piston.

2. In a pump as claimed in claim 1 the provision of annular packing rings for each valve, a spindle for the valve, a disc rotatably mounted on said spindle, radial fingers on said disc and means carried by the spindle for urging said fingers against the packing rings. 65

3. A pump chiefly for concrete, mortar and the like material comprising a cylinder, a piston, control means for making said piston reciprocate inside said cylinder, two valve casings the walls of which continue directly the wall of the cylinder and located towards one end thereof, said casings opening into the cylinder at points located close one another and having a wall in common at said points of close location, said casings having outer openings respectively for suction 70
75

- and exhaust, suction and exhaust ducts connected with the outer openings in the corresponding casings, a valve arranged in each casing and provided with a substantially diametrical passageway one end of which is adapted to register with the opening of the casing into the cylinder and the other end of which has a flaring shape for one of said valves and is adapted to register with the outer opening of its casing and means for controlling said valves in operative relationship with the movements of the piston.
4. In a pump as claimed in claim 1 a perforated plug adapted to be removably fitted inside the diametrical passageway of each valve during the scavenging with water and to restrict the passageway to an extent as will prevent altogether communication of the cylinder with the exhaust means for one valve and with the suction means for the other for a predetermined angular position of the valve considered.
5. A pump chiefly for concrete, mortar and the like material comprising a cylinder, a piston, control means for making said piston reciprocate inside said cylinder, suction means for said cylinder including a rotary valve and provided with a suction opening, exhaust means for said cylinder including a rotary valve and provided with an exhaust opening, said valves being provided with a substantially diametrical passageway one end of which is adapted to open towards the cylinder and the other end of which is adapted to open flaringly to the corresponding opening and means for controlling said valves in operative relationship with the movements of the piston,
- 25 30 35
- 30 said means including cams adapted to provide a uniformly accelerated start and a uniformly decelerated stop motion for the valves at each operation thereof.
6. A pump chiefly for concrete, mortar and the like material comprising a cylinder, a piston, control means for making said piston reciprocate inside said cylinder, suction means for said cylinder including a rotary valve and a casing therefor provided with two substantially opposite openings one of which is in substantially immediate communication with the cylinder, exhaust means for said cylinder including a rotary valve and a casing therefor provided with two substantially opposite openings one of which is in substantially immediate communication with the

cylinder, said valves being provided each with a substantially diametrical passageway the ends of which are adapted to register with the corresponding openings of the corresponding valve casing while the end of the passageway which is adapted to register with the casing opening remote from the cylinder has a flaring shape and means for controlling said valves in operative relationship with the movements of the piston.

7. A pump chiefly for concrete, mortar and the like material comprising a cylinder, a piston, control means for making said piston reciprocate inside said cylinder, two valves casings the walls of which continue directly the wall of the cylinder and located towards one end thereof, said casings opening into the cylinder at points located close one another and having a wall in common at said points of close location, said casings having outer openings respectively for suction and exhaust, suction and exhaust ducts connected with the outer openings in the corresponding casings, a valve arranged in each casing and provided with a substantially diametrical passageway one end of which is adapted to register with the opening of the casing into the cylinder and the other end of which has a flaring shape for each of said valves and is adapted to register with the outer opening of its casing and means for controlling said valves in operative relationship with the movements of the piston.

8. A pump chiefly for concrete, mortar and the like material comprising a cylinder, a piston, control means for making said piston reciprocate inside said cylinder, suction means for said cylinder including a rotary valve, exhaust means for said cylinder including a rotary valve and provided with a suction opening, said valves and provided with an exhaust opening being provided with a substantially diametrical passageway one end of which is adapted to open towards the cylinder and the other end of which has a flaring shape for each of said valves and is adapted to register with the corresponding opening and means for controlling said valves in operative relationship with the movement of the piston, said means including cams adapted to provide a uniformly accelerated start and a uniformly decelerated stop motion for the valves at each operation thereof.

ROGER LONDAIS.
